UNITED STATES PATENT OFFICE.

GARRISON BABCOCK, OF ROCHESTER, NEW YORK, ASSIGNOR TO MERTON E. LEWIS, OF ROCHESTER, NEW YORK.

SIGNALING SYSTEM.

No. 887,748.

Specification of Letters Patent.

Patented May 19, 1908.

Application filed July 7, 1905. Serial No. 268,755.

To all whom it may concern:

Be it known that I, GARRISON BABCOCK, citizen of the United States, residing at Rochester, in the county of Monroe and State of New York, have invented a certain new and useful Improvement in Signaling Systems, of which the following is a full, clear, concise, and exact description, reference being had to the accompanying drawings, forming a part of this specification.

My invention relates to combined telephone and telegraph systems, particularly to systems used in municipalities where the same line is used for transmitting fire alarm signals and for transmitting telephone and telegraphic signals and messages, that is, a line which may be used in common by the fire department and the police department.

In my Patent No. 807,235, dated December 12, 1905, I describe a system adapted to such use, but in this patent the chief object of my invention is to provide locking-out means whereby when one substation is in use for telegraphic or telephonic purposes another station is prevented from using the line or interfering with the conversation or signals from the first station, and to provide means whereby the line is at all times in perfect condition to transmit fire alarm signals independently of the telegraph or telephonic apparatus and circuits.

My invention can be best understood by reference to the accompanying drawing in which I diagrammatically illustrate a line connecting at one end with the central station signal receiving apparatus and at the outside connecting with fire alarm substations and with telegraphic and telephonic substations.

The main line consisting of the line limbs *a* and *b* is normally closed through a central battery or other source of current 1. At the central station a nonsensitive relay 2 and a sensitive relay 3 are included serially in the line, and the primary winding 4 of an induction coil is also serially included in the line, the secondary winding 5 of the induction coil being connected to the sleeve and tip strand springs 6 and 7 of the telephonic spring jack 8 at the central exchange. The cord circuit 50 at the central exchange has the answering plug 9 and the calling plug 10 connected with the listening key 11 and the calling key 12, the action of the calling key 12 causing connection with the plug 10 of a source 13 of ringing or signaling current, while actuation

of the key 11 connects the operator's telephone apparatus 14 with the answering plug, and actuating spring 15 is mechanically connected with the sleeve spring 6 which spring 15 normally engages the contact spring 16, and upon insertion of the plug within the jack engages the alternate contact spring 17. The actuating spring 15 is connected with the line at the central station side of the repeating or induction coil, while the contact spring 16 engages the line at the other side of the induction coil, the primary winding of the induction coil being thus short-circuited when the plug is removed from the jack. The alternate spring 17 is connected with the line so that upon insertion of the plug in the jack the relays 2 and 3 will be short-circuited as the actuating spring 15 engages the alternate spring 17, the primary winding being then included in circuit upon disengagement of the actuating spring from the normal contact spring 16.

At each of the fire alarm stations F, of which there may be any number, is a normally closed circuit breaker 18 having mechanical connection with the code wheel 19 in such a manner that upon rotation of the code wheel in a manner well known in telephonic art the circuit breaker will be repeatedly opened, thereby to repeatedly open the line *a*—*b*.

At each telegraphic and telephonic station, of which there may be any number, there is provided a controlling solenoid switch 20. This solenoid switch consists of the core 21 suspended at its ends from the pivot hangers 22 and 23. The greater or front part 24 of the core is of magnetic material, preferably stranded iron, while the rear part 25 is of non-magnetic material such as aluminum or brass. The magnetic frame 26 of the switch surrounds and protects the winding 27, the greater part of which winding encircles the magnetic part of the core so that upon proper current flow the core will be attracted. The front end of the core is provided with a cap or abutment 28 for engaging the frame 26 after the core has been attracted its full distance. Extending from the hanger 23 is a contact arm 29 engaging the contact 30 being preferably a mercury cup so that the contact between the mercury and the arm 29 will not be broken until the cap 28 of the core has been brought into engagement with the magnetic frame 26.

The apparatus at the telephone and telegraph stations may be inclosed in a box, in which are provided the contacts 31 and 32 which are in engagement when the box is closed but which are carried out of engagement when the box is opened. The box is also provided with a lock 33 to the rear of which at the interior of the box is provided spring jack mechanism 34 consisting of the sleeve spring 35 and the tip spring 36 adapted for engagement with the sleeve and tip contacts 37 and 38, respectively, of the key 39. This key is of the construction shown and is provided with the code wheel 40 and the circuit breaking switch 41 connected with the tip and sleeve members 37 and 38, the key being also provided with spring actuating mechanism not shown, whereby the code wheel 40 is revolved after the key has been inserted through the lock and into engagement with the springjack 34, insertion of the key also causing disengagement of the contacts 42 and 43 associated with the springjack. Normally the main line is continuous through each substation along a circuit serially including the contacts 31 and 32 and the jack contacts 42 and 43, the line connecting with this circuit at the main binding posts 44 and 45. One terminal of the solenoid winding 27 connects with the binding post 44 and the other terminal thereof connects with the contact arm 29, the contact 30 being connected with the binding post 45. One terminal of a winding 46 having a high impedance with a comparatively low resistance connects with the arm 29 and the other terminal thereof connects with the contact 30, this winding being thus normally short-circuited. Telephonic apparatus consisting of the receiver 47 and the transmitter 48 are serially connected in circuit with the contact arm 29 and contact 30 in bridge of the winding 46. The normally open switch 49 is connected in bridge of both the winding 46 and the telephonic apparatus and is associated with the code wheel 50 which upon actuation will cause repeated closure of the switch 49 and thus short-circuiting of the winding 46 and telephonic apparatus. A switch hook 51 for holding the receiver is associated with the switch 52 to close said switch when the receiver is on the hook. Said switch is connected serially in a circuit bridging the winding 46 and the telephonic apparatus and normally including the tip spring 36 and the normal contact spring 53 of the spring jack. Thus under normal conditions the line is continuous at each telephonic substation through the path of no resistance containing the contacts 31, 32, 42 and 43, all apparatus within the box being thus short-circuited. Upon opening of the box, however, this short path is opened, and the winding 27 of the solenoid switch 20 will then primarily be the only apparatus in circuit, the winding 46 and tele-

phonic apparatus being still short-circuited through the arm 29 and contact 30. As will be described later, the solenoid, however, becomes energized to open the circuit between the arm 29 and the contact 30 whereupon the winding 46 and the telephonic apparatus will be connected in parallel and in series with the solenoid, the apparatus being adapted for telephonic communication.

The main battery at the central exchange may be adjusted to deliver say 130 milli-amperes under normal conditions when the substations are not in use, and it practically delivers this current when the solenoid 27 at a substation is in circuit, these solenoids having a very low resistance. The relay 2 included serially in the main line is adjusted to become deenergized only upon an absolute break in the line, while the relay 3 is more sensitive and will release when the current flow falls below say 90 milli-amperes. The armature 54 is normally attracted by the relay 2 away from its contact 55, and the armature 56 of the relay 3 is normally attracted away from its contact 57. One terminal of the battery 58 connects with the contacts 55 and 57, while the other terminal of the battery connects with one terminal of a registering device 59 whose other terminal connects through the conductor 60 and conductor 61 with the armature 54, the conductor 61 including the electromagnet 62 also associated with the armature 56. A lamp 63 or other indicating signal connects with the armature 56 and with the conductor 60.

The operation of the system now becomes apparent. Starting with all the substation apparatus in its normal condition, suppose an alarm of fire is to be sent to the central station. The code apparatus F at the proper fire alarm station is set in operation to repeatedly open the switch 18, whereupon current flow through the main line is repeatedly interrupted. Each interruption of the current causes release of the relays 2 and 3. The armature 54 of the relay 2 engages its contact 55 and a circuit is closed from the battery 58 through the register mechanism 59, through the conductor 60, through conductor 61, through the winding of the electromagnet 62 to the armature 54 and from the contact 55 back to the battery. Deenergization of the relay 3 has a tendency to release the armature 56, but this is prevented by the electromagnet 62 included in the circuit just traced. The lamp 63, therefore, is prevented from being included in circuit and consequently is not affected, and where the central operator receives signals on the register device 59 only, she knows that the signal emanates from the fire alarm box.

If it is desired to have telephonic conversation with the central exchange, for instance, a police officer desiring to report to the proper officer at the central exchange, the

apparatus at one of the substations T is utilized. The officer inserts his key into the lock and into the springjack thereby breaking connection between the contacts 42 and 5 43 whereby the short circuit path through the substation is broken and the solenoid 27 included in circuit, as before described. The dimensions of the winding 27 and the adjustment of the core and pivoting supports there- 10 for are such that the core will be started only when the current flow is at or very close to the maximum current flow, in this case 130 milli-amperes. This current primarily flows through the winding upon breaking of the 15 short circuit path, and the core is immediately pulled inwardly to bring the cap 28 into engagement with the magnetic frame 26. Upon consequent disengagement of the arm 29 from the contact 30 the impedance wind- 20 ing 46 and telephonic apparatus will be included serially in circuit and in series with the solenoid 27, as before described, this inclusion in circuit of the winding 46 and telephonic apparatus being practically simulta- 25 neous with the insertion of the key in the lock. Upon insertion of the key in the springjack also the contact is broken between the tip spring 36 and the normal contact spring, and the switch 41 is connected 30 with the tip and sleeve contacts of the spring- jack. The circuit which now serially in- 35 cludes the switch 52 held closed by the receiver hook and the switch 41 after insertion of the key short-circuits the telephonic appa- 40 ratus and the winding 46, that is, only the low resistance of the solenoid 27 is in circuit. Upon turning of the key, however, to open the lock the code wheel 40 will be actuated to cause repeated opening of the switch 41 and 45 of this short circuit, whereby the parallel re- sistance of the winding 46 and the telephonic apparatus will be alternately included in the line which will reduce the current flow there- through to 90 milli-amperes and thus the 50 current flow in the line will alternate from the maximum value or 130 milli-amperes to the minimum value or 90 milli-amperes, this continuing until the proper code signals have been sent from the key, these signals corre- 55 sponding to the number of the particular key used. This variation in current from 130 to 90 milli-amperes affects only the relay 3, the relay 2, as before described, being responsive only to absolute breaks in the line. Upon 60 each reduction in current, therefore, the relay 3 will release its armature 56 which, upon engagement with its contact 57, closes the following circuit: from the battery 58 through the register device 59, conductor 60, lamp 63, armature 56, and from contact 57 back to the battery, both the registering de- 65 vice and the lamp responding, the registering device causing a record to be made.

Having actuated the key to open the box, 65 the officer removes the receiver from the

hook to open the circuit which would otherwise short-circuit the winding 46 and the telephonic apparatus, and he then causes actuation of the break wheel 50 for causing repeated closure of the switch 43, this switch, 70 as before described, being adapted upon closure also to short-circuit the winding 46 and the telephonic apparatus. This actuation of the break wheel 50, therefore, causes current fluctuations through the line to 75 actuate the relay 3 in a similar manner as upon actuation of the code wheel 40 in the officer's key, the signal sent by the wheel 50, however, corresponding to the location number of the box. Having thus communicated 80 to the central exchange the number of his key and the location of the station from which he is communicating, the officer through the telephonic apparatus may converse with the central attendant to give in- 85 formation or to receive orders or to call for some outside connection. The central operator upon observing a continued illumination of the lamp 63 will know that the officer desires to converse, otherwise the lamp would 90 have become extinguished after flashing the signal giving the location number of the calling station. Central then inserts the an- 95 swering plug of the cord circuit into the jack and upon actuation of the listening key is in 100 telephonic communication with the officer, the short circuit about the primary winding 4 including the contacts 15 and 16 having been opened upon insertion of the plug. The insertion of the plug also engages the 105 spring 15 with the spring 17 to short-circuit the relays 2 and 3 and thus impedance of the said relays is removed from the telephonic circuit. The system, however, is always in balance as the resistance of the primary 110 winding is equal to the combined resistance of the relays 2 and 3. After desired con- 115 versation has been completed, the officer hangs up the receiver, closes the door of the station box and removes the key to restore 119 the apparatus and line to its normal condition.

It has been before stated that the core 24 could be started only when maximum current flowed through the solenoid 27 and there would, therefore, be a tendency for the solenoid to release the core upon flow of minimum current through the line which, as just described, will happen during the op- 120 eration of the telegraphing signal apparatus. However, when the cap 28 of the core comes into engagement with the magnetic frame 26 less current is required to maintain the core in its attracted position than was re- 125 quired to start the core from a state of rest, this being well known in the art. The core, therefore, remains attracted to maintain dis- 130 connection of the arm 29 and contact 30 until the station box is closed and the key removed from the lock. During telephonic 130

conversation from one substation the current flow will be reduced, in this case to 90 milliamperes owing to the resistance of the winding 46 and the telephonic apparatus. 5 As before stated, it requires the full maximum current flow to cause a solenoid core to be started, and therefore, even though the box at another substation be opened, the solenoid core thereat will not respond and 10 the contacts 29 and 30 at this other substation will not be disconnected but will maintain the short circuit about the telephonic and telegraphic apparatus, and signaling from the second box will be entirely locked 15 out. The officer at the second station then upon removing the receiver immediately ascertains whether he has connection with central. If he has such connection he hears the clicks in the receiver upon operation of 20 the corresponding break wheel 50. If the line, however, is busy elsewhere and the current, as before described, is not sufficient to have actuated the solenoid upon opening of the box, the telephonic apparatus, therefore, 25 remains short-circuited and irresponsive. The solenoid switch 20 may, therefore, be called a lock-out switch or relay.

Another very important feature of my invention, besides the lock-out feature just described, is the provision for at all times maintaining the main line in perfect condition for transmitting calls from fire alarm stations, the fire alarm service being the most important in such systems. If, therefore, conversation 30 were being carried on at one of the telephonic substations and apparatus were set in operation at one of the fire alarm stations, the solenoid at the busy station would become immediately deenergized upon breaking 35 of the line at the fire alarm apparatus, and the telephonic and telegraphic apparatus at the busy station would be rendered inoperative. Should this happen, however, the officer who is telephoning will know that a 40 fire alarm is being sent in over the line and he can then ascertain where the alarm is sent from, and if the fire is in his neighborhood he can go there and lend assistance. He can ascertain the location of the actuated fire 45 alarm box by listening in the receiver or by listening to the clicks produced by the solenoid switch, the core of the solenoid being attracted at each closure of the line at the actuated fire alarm apparatus. Officers at any 50 other telephone substations along the same line will also, upon opening the box, be notified that an alarm of fire is being sent in, and by listening in the receiver or to the solenoid switch they also can ascertain where the fire 55 is and go there if necessary. This listening to the fire alarm signal at more than one substation on a line is rendered possible because the windings 27 of the solenoid switches are of very low resistance and their serial inclusion 60 in the line upon closure of the line at the call-

ing fire alarm station will not reduce the current flow perceptibly, and the line, therefore, even though substation boxes were opened and the receivers off the hooks, will be practically at its normal strength and thus in no way interfere with the most efficient transmission of the fire alarm signals. 70

If it were not for the low resistance winding 46, the current flow through the main circuit would be materially weakened owing to 75 the comparatively high resistance of the telephonic apparatus which would be telephonically included serially in the line. Being bridged, however, by the comparatively low resistance winding 46, the resistance in the 80 main line is sufficiently reduced, so that, upon actuation of fire alarm apparatus sufficient direct current will flow to efficiently actuate the proper alarm apparatus. The winding 46, however, has high impedance 85 and the telephonic currents will all flow through the telephonic apparatus. The winding 46 is in circuit in the main line only at the beginning of a fire alarm signal, being shunted from circuit by the contacts 29 and 30 upon deenergization of the solenoid 20 when the line is first broken at the fire alarm station, and thereafter the line will have only the very low resistance of the solenoid windings. Provision may also be made for repeating the signals from the central exchange and repeating means such as an ordinary repeating relay 64 may be included serially in the main line at the central exchange and the circuits 65 controlled by this relay may 90 lead to sub-central or precinct stations, or elsewhere. 95

The transmitter and receiver at the substations are relatively connected as shown, the transmitter being included serially in circuit between the receiver coils 66 and 67. 105

I thus provide a very simple and efficient combination system in which fire alarm signals and telephonic and telegraphic signals may be transmitted over a common line, the 110 fire alarm, telephonic and telegraphic signals being analyzed at the central exchange and received by distinctive receiving apparatus. The line, however, is at all times in perfect condition for receiving the more important 115 fire alarm signals, the telephonic and telegraphic apparatus when such fire alarm systems are given being for the time removed from circuit. At the same time, however the fire alarm signal can be heard and interpreted 120 at any of the telephonic substations. During the use of the line for telephonic conversation from one substation, all other telephonic and telegraphic substations are locked against use. Police or other officer may communicate to the central attendant the number of his key, the number of the station from which he calls and hold telephonic conversation, the communication of the number of the key being given automatically during the 125 130

operation of the opening in the substation box, and either, any or all of these signals may be communicated as desired. The fire alarm apparatus and the telephone-telegraph apparatus may be at separate substations or may be all included at the same substation.

I do not wish to be limited to the precise arrangement of the apparatus and circuits as shown, as changes may readily be made without departing from the spirit of my invention.

I wish to secure by Letters Patent:

1. In a signaling system, the combination with a normally closed main circuit extending from a central exchange, of a main source of current in said line, non-sensitive signal receiving apparatus at the central exchange responsive to only interruptions in the line, sensitive signal receiving apparatus at the central exchange responsive to current changes in the line, substations connected with the line, means at each substation for opening and closing the line whereby the non-sensitive receiving apparatus at the central exchange is effective, telephonic apparatus at each substation adapted for serial inclusion in the line, the resistance of said telephonic apparatus tending to diminish the current flow through said line, and means for preventing such diminution of current when the means are actuated which open and close the line to cause actuation of the non-sensitive receiving apparatus at the central exchange.
2. In a signaling system, the combination with a normally closed main line leading from a central exchange, of a source of current in said line, non-sensitive signal receiving apparatus at the central exchange responsive to only interruptions of the line, sensitive signal receiving apparatus at the central exchange responsive to current changes in the line, substations connected with the line, fire alarm apparatus at each substation adapted upon actuation to repeatedly open the line whereby to cause actuation of the non-sensitive receiving apparatus, telephonic apparatus at each substation, electromagnetic means at each substation normally short-circuited to render the telephonic apparatus inoperative, means for removing the short-circuit from the electromagnetic mechanism whereby said mechanism becomes active to cause connection of the telephonic apparatus in the main line thereby causing diminution of current flow through the line whereby the sensitive receiving apparatus at the central exchange is actuated, and means for removing the resistance of the telephonic apparatus from the main line upon actuation of fire alarm apparatus connected with the line.
3. In a signaling system, the combination with a normally closed main line leading from a central exchange to substations, of a source of current in the line, fire alarm apparatus at each substation for opening and closing the line, non-sensitive signal receiving apparatus at the exchange responsive only to actuations of fire alarm apparatus to open the line, sensitive signal receiving apparatus at the exchange responsive only to current changes in the line, telephonic apparatus at each substation normally disconnected from the line, means upon actuation of apparatus at a substation for causing said telephonic apparatus to be serially included in the line; the resistance upon inclusion of the telephonic apparatus causing the current flow through the circuit to be reduced and the sensitive apparatus actuated, and means at each substation for rendering ineffective the resistance of the telephonic apparatus upon actuation of fire alarm apparatus when said telephonic apparatus is in use, whereby the current in the circuit assumes its normal value.
4. In a signaling system, the combination with a normally closed main line leading from a central exchange to substations, of a source of current in the line for causing a normal maximum current flow, fire alarm apparatus at each substation adapted upon actuation to repeatedly open the line, non-sensitive signal receiving apparatus at the central exchange responsive only to actuations of fire alarm apparatus, signal receiving apparatus at the exchange responsive upon reduction of current flow in the circuit, telephonic apparatus at each substation normally disconnected from circuit, apparatus at each substation adapted upon actuation to cause connection of said telephonic apparatus in the line, the resistance of said telephonic apparatus causing reduced current flow through the line whereby the sensitive receiving apparatus is actuated, and an impedance coil of low resistance connected in bridge of the telephonic apparatus whereby normal current will flow through the line upon actuation of the fire alarm apparatus.
5. In a signaling system, the combination with a normally closed main line leading from a central exchange to substations, of a source of current in said line for normally delivering maximum current flow, fire alarm apparatus at each substation adapted upon actuation to repeatedly open the line non-sensitive receiving apparatus at the central exchange responsive to actuations of fire alarm apparatus, sensitive receiving mechanism at the central exchange responsive upon diminution in current flow through the line, telephonic apparatus at each substation normally disconnected from the line, normally inert electromagnetic mechanism controlling the connection of said telephonic apparatus with the line, means upon actuation of substation apparatus for causing actuation of said electromagnetic mechanism to cause

of current in the line, fire alarm apparatus at each substation for opening and closing the line, non-sensitive signal receiving apparatus at the exchange responsive only to actuations of fire alarm apparatus to open the line, sensitive signal receiving apparatus at the exchange responsive only to current changes in the line, telephonic apparatus at each substation normally disconnected from the line, means upon actuation of apparatus at a substation for causing said telephonic apparatus to be serially included in the line; the resistance upon inclusion of the telephonic apparatus causing the current flow through the circuit to be reduced and the sensitive apparatus actuated, and means at each substation for rendering ineffective the resistance of the telephonic apparatus upon actuation of fire alarm apparatus when said telephonic apparatus is in use, whereby the current in the circuit assumes its normal value.

4. In a signaling system, the combination with a normally closed main line leading from a central exchange to substations, of a source of current in the line for causing a normal maximum current flow, fire alarm apparatus at each substation adapted upon actuation to repeatedly open the line, non-sensitive signal receiving apparatus at the central exchange responsive only to actuations of fire alarm apparatus, signal receiving apparatus at the exchange responsive upon reduction of current flow in the circuit, telephonic apparatus at each substation normally disconnected from circuit, apparatus at each substation adapted upon actuation to cause connection of said telephonic apparatus in the line, the resistance of said telephonic apparatus causing reduced current flow through the line whereby the sensitive receiving apparatus is actuated, and an impedance coil of low resistance connected in bridge of the telephonic apparatus whereby normal current will flow through the line upon actuation of the fire alarm apparatus.

5. In a signaling system, the combination with a normally closed main line leading from a central exchange to substations, of a source of current in said line for normally delivering maximum current flow, fire alarm apparatus at each substation adapted upon actuation to repeatedly open the line non-sensitive receiving apparatus at the central exchange responsive to actuations of fire alarm apparatus, sensitive receiving mechanism at the central exchange responsive upon diminution in current flow through the line, telephonic apparatus at each substation normally disconnected from the line, normally inert electromagnetic mechanism controlling the connection of said telephonic apparatus with the line, means upon actuation of substation apparatus for causing actuation of said electromagnetic mechanism to cause

serial inclusion of the telephonic apparatus in the line, an impedance winding connected in bridge of the telephonic apparatus, and means for repeatedly short-circuiting the 5 telephonic apparatus and the impedance winding, whereby the resistance thereof is removed from circuit and the sensitive receiving apparatus is repeatedly actuated.

6. In a signaling system, the combination 10 with a normally closed main circuit extending from a central exchange to substations, of a source of current for said main circuit, signal receiving apparatus at the central exchange, telephonic apparatus at each substation normally disconnected from circuit, normally inert electromagnetic mechanism at each substation controlling the connection of the telephonic apparatus with the line, means upon actuation of substation apparatus 15 for causing actuation of the electromagnetic mechanism to cause the telephonic apparatus to be included serially in the line with said electromagnetic mechanism, and an impedance winding connected in bridge 20 of the telephonic apparatus, the resistance of the impedance winding being very small whereby normal flow is maintained through the line, the impedance of said winding, however, causing telephonic currents to be unaffected and to pass through the telephonic 25 apparatus.

7. In a signaling system, the combination 30 with a normally closed line leading from a central exchange to substations, of a source of current in said line, signal receiving apparatus at the central exchange, controlling electromagnetic mechanism at each substation, said electromagnetic mechanism being normally short-circuited but adapted upon 35 actuation of substation apparatus to be included serially in the line, telephonic apparatus at each substation adapted upon actuation of the electromagnetic mechanism to be included serially in circuit with said electromagnetic mechanism, and a winding of low 40 resistance and high impedance connected in bridge of the telephonic apparatus whereby the direct current flow through the line is unaffected and whereby telephonic currents 45 are caused to flow through the telephonic apparatus.

8. In a signaling system, the combination 50 with a normally closed main line leading from a central exchange to substations, of a source of current in said main line, signal receiving apparatus at the central exchange, telephonic apparatus at each substation, means at each substation for normally short-circuiting the telephonic apparatus thereat 55 from circuit, a relay at each substation controlling the short circuiting means for said telephonic apparatus, and means upon actuation of substation apparatus for causing said relay and said telephonic apparatus to be 60 connected serially in the main line, the cur-

rent flow upon connection in circuit of telephonic apparatus at one substation being insufficient to cause actuation of the relay at another substation whereby the telephonic apparatus at said other substation is locked 70 from circuit.

9. In a signaling system, the combination 75 with a main line extending from a central exchange to a substation, of a source of current for said line, signal receiving apparatus at the central exchange, telephonic apparatus at each substation, a relay at each substation normally causing said telephonic apparatus to be short-circuited, means upon actuation of substation apparatus for primarily allowing current flow through said relay whereby said relay becomes actuated, means upon actuation of said relay for eventually removing the short-circuit from the telephonic apparatus whereby said telephonic apparatus 85 becomes effective, the current flow through the main line upon telephonic apparatus at one substation becoming effective being insufficient to cause actuation of the relay at another substation whereby the telephonic 90 apparatus at said other substation remains ineffective.

10. In a signaling circuit, the combination 95 with a main line leading from a central exchange to substations, of a source of current for the line, signal receiving apparatus at the central exchange, telephonic apparatus at each substation, a relay at each substation normally causing short-circuiting of the corresponding telephonic apparatus, the relay 100 being normally short-circuited, and means upon actuation of substation apparatus for primarily causing current flow only through the corresponding relay whereby the relay is actuated to eventually open the short circuit 105 about the telephonic apparatus to cause the telephonic apparatus to be included serially in the main line with the relay, said relay requiring less current after actuation thereof to maintain it in an actuated position, the 110 current flow through the line, however, upon inclusion in circuit of the telephonic apparatus at one substation being reduced and insufficient to cause actuation of the relay at another substation whereby the telephonic 115 apparatus at said other substation remains short-circuited.

11. In a signaling system, the combination 120 with a main line leading from a central exchange to a plurality of substations, of a source of current for the main line, signal receiving apparatus at the central exchange, telephonic apparatus at each substation, a relay at each substation adapted when inert to short-circuit the telephonic apparatus, 125 each relay being normally short-circuited, said relay requiring greater current flow to be started and less current flow to maintain it in an actuated position, and means upon actuation of substation apparatus whereby 130

- the corresponding relay is primarily included alone in circuit whereby sufficient current will flow to cause its actuation, the telephonic apparatus at the substation being included serially in circuit with the relay upon actuation of the relay, the diminished current flow upon inclusion of the telephonic apparatus causing actuation of the receiving apparatus at the central exchange, the diminished current flow being insufficient to cause actuation of the controlling relay at any other substation whereby the telephonic apparatus at the other substations remain short-circuited.
- 15 12. In a signaling system, the combination with a normally closed main circuit leading from a central exchange to substations, of a source of current for the main circuit, signal receiving apparatus at the central exchange responsive to diminution of current flow in said circuit, telephonic apparatus at each substation, a controlling relay at each substation normally causing short-circuiting of the telephonic apparatus thereat, each relay being normally short-circuited, means whereby each relay requires greater initial current flow to cause its actuation and less current flow to maintain it in an actuated position, means upon actuation of substation apparatus for removing the short circuit from the relay and causing serial inclusion of the relay in the main circuit, and means for maintaining the relay alone in circuit for an interval to allow it to become actuated, the telephonic apparatus after actuation of the relay being rendered effective and included serially in the main circuit with the relay, the increased resistance due to the telephonic apparatus causing sufficient diminution in current flow whereby the signal receiving apparatus at the central exchange is actuated, the current flow upon inclusion in circuit of the telephonic apparatus at one substation being insufficient to cause effective actuation of the relay at another substation on the line whereby the telephonic apparatus at all other substations remains short-circuited.
13. In a signaling system, the combination with a normally closed main line leading from a central exchange to substations, of a source of current for the line, fire alarm apparatus at each substation adapted upon actuation to repeatedly open the line, receiving apparatus at the central exchange, responsive only to actuations of fire alarm apparatus, additional receiving apparatus at the central exchange responsive to current reduction in the line, telephonic apparatus at each substation, a relay at each substation normally causing the telephonic apparatus to be short-circuited, means upon actuation of substation apparatus for causing said relay and said telephonic apparatus to be serially included in the main line whereby the telephonic apparatus becomes effective, and an impedance winding of low resistance bridging the telephonic apparatus whereby the main line may at all times carry sufficient current to efficiently actuate the receiving apparatus upon actuations of fire alarm apparatus, the combined resistance of the relay, the impedance winding and telephonic apparatus causing sufficient current reduction in the line to actuate the additional receiving apparatus at the central exchange.
14. In a signaling system, the combination with a normally closed main line leading from a central exchange to a plurality of substations, of a source of current in said line, signal receiving apparatus at the central exchange responsive to current reductions in said line, telephonic apparatus at each substation, a relay at each substation for normally short-circuiting the telephonic apparatus from circuit, said relay being normally short-circuited and adapted upon actuation of substation apparatus to be included serially in the main circuit with the telephonic apparatus, inclusion in circuit of the relay and telephonic apparatus causing diminished current flow whereby the signal receiving apparatus at the central exchange is actuated, and telegraphic apparatus at each substation for repeatedly short-circuiting the telephonic apparatus whereby the resistance of the telephonic apparatus is repeatedly removed from circuit and the receiving apparatus at the central exchange repeatedly actuated.
15. In a signaling system the combination with a normally closed main line leading from a central exchange to substations, of a source of current in said main line, telephonic apparatus at each substation, a relay at each substation normally in position to cause short circuiting of the telephonic apparatus, a box inclosing the apparatus at each substation and provided with a lock, means adapted upon insertion of a key in said lock to cause actuation of the relay to open the short circuit path about the telephonic apparatus and to cause inclusion of said relay serially in circuit in the main line with the telephonic apparatus.
- In witness whereof, I hereunto subscribe my name this first day of July A. D., 1905.
- GARRISON BABCOCK.
- Witnesses:
- CHARLES J. SCHMIDT,
LEONARD W. NOVANDER.
